(57) **CLAIM**

The ornamental design for a tire, as shown on FIGS. 1 to 5 and described.

DESCRIPTION

FIG. 1 is the front elevational view of a tire, for which the other sides, include rear, top and bottom elevational views being identical thereto;

FIG. 2 is a left side elevational view thereof;

FIG. 3 is a right side elevational view thereof;

FIG. 4 is an enlarged view of the portion as defined in marker lines 4-4 in FIG. 1; and,

FIG. 5 is a perspective view of a tire showing the new design, it being understood that the pattern repeats uniformly throughout the circumference of the tread.

The broken lines showing the sidewall and tire interior form no part of the claimed design.
